UNITED STATES PATENT OFFICE.

JOHN J. BENTZ, OF NEW YORK, N. Y., ASSIGNOR TO GEORGE BENTZ, OF NEW YORK, N. Y.

NUT-LOCK.

1,369,002.

Specification of Letters Patent. Patented Feb. 22, 1921.

Application filed April 17, 1918. Serial No. 229,194.

To all whom it may concern:

Be it known that I, JOHN J. BENTZ, a citizen of the United States, residing at Bronx, county of Bronx, and State of New York, have invented certain new and useful Improvements in Nut-Locks, of which the following is a specification.

This invention relates to means for securing nuts with relation to their bolts, so that 10 the same may not become loosened.

The principal object of the invention is to provide means co-operative with the nuts and bolts, by which the nuts are prevented from movement when set in adjustment.

15 A further object is to provide a securing device the ends of which are so formed as to engage respectively with the bolts and nuts, all of several parts being of simple construction and readily manufactured.

20 These and other like objects are attained by the novel construction and combination of parts hereinafter described and shown in the accompanying drawing, forming a material part of this disclosure, and in 25 which:—

Figure 1 is a side elevational view, partly in section showing a bolt and nut made in accordance with the invention.

Fig. 2 is a top plan view of the same.

30 In the drawing 10 indicates the shank or body of the bolt which on one end is provided with the customary head 11 while its opposite end 12 is screw-threaded as usual.

As shown, the screw-threaded portion 12 35 is provided with a longitudinally extending slot 16 passing transversely across the convolutions of the thread, the slot being adapted to contain the body of a key 17.

The slot 16 has formed with it a plurality 40 of lateral, inwardly extending recesses 22 receivable of the bent end 18 of the key 17, the upper end of which is formed into an outwardly extending element 23, terminating in a downturned hooked portion 24, engageable within any of a plurality of openings 25 formed in the top of the nut 26, while a lug 28 extends outwardly and downwardly from the key 17 below the bent end 18.

50 It will be clear that the lug 28 can be engaged by a bar or the like for springing the

key sufficiently out of the slot 16 to permit the bent end 18 to clear or to be retracted from any of the several recesses 22. The longitudinal slot 16 is deep enough to accommodate the key 17 entirely, and a groove 55 21 in the nut 26 allows a certain play of the key 17 when the bent end 18 of the same is sprung out of the recesses 22.

In operation, the key 17 is placed into the 60 slot 16 with its bent end 18 engaging any of the recesses 22, then the nut is screwed home and the upper end of the key is then bent by a suitable tool to engage any of the openings 25. When it is desired to release the 65 nut, the upper bent end of the key is straightened by a suitable tool and with the assistance of the unscrewing nut, and then the bent end 18 is sprung out of the respective recesses 22 by a tool engaging the 70 lug 28.

Having thus described my invention what I claim as new and desire to secure by Letters Patent, is:

In a device of the character described, a 75 threaded shank having a longitudinal slot and a plurality of inwardly extending recesses, a nut threaded on the shank, and having a groove in its body, and a plurality of openings formed in its top, and a key adapted to be received in the longitudinal slot of 80 said shank, an outwardly extending element at the upper end of said key, terminating in a downturned hooked portion adapted to engage in any of said plurality of openings 85 in said nut, a bent end at the lower end of said key, adapted to engage in any of said inwardly extending recesses, said hooked portion allowing a springing of the key 90 sufficiently to permit a retraction of said hooked portion from the opening in said nut by a tool, a lug extending outwardly and downwardly from the lower bent end of said key, adapted to be engaged by a tool for 95 springing said bent end of the key out of one of the recesses in said shank, the groove in said nut permitting the key to be sprung out of said recesses when the nut is on the shank.

In testimony whereof I have affixed my 100 signature.

JOHN J. BENTZ.
